CLAIM

The ornamental design for a weekender travel bag, as shown and described.

DESCRIPTION

FIG. 1 shows a front perspective view of the weekender travel bag;

FIG. 2 shows a front view of the weekender travel bag;

FIG. 3 shows a rear view of the weekender travel bag;

FIG. 4 shows a left side view of the weekender travel bag;

FIG. 5 shows a right side view of the weekender travel bag; and,

FIG. 7 shows a bottom side view of the weekender travel bag.

The broken lines illustrate portions of the weekender travel bag and form no part of the claimed design.
